(57) **CLAIM**

An ornamental design for a razor handle, as shown and described.

DESCRIPTION

FIG. 1 is a front perspective view of a razor handle showing my new design;

FIG. 2 is a left side elevational view thereof;

FIG. 3 is a right side elevational view thereof;

FIG. 4 is a front view thereof;

FIG. 5 is a rear view thereof;

FIG. 6 is top plan view thereof; and,

FIG. 7 is a bottom plan view thereof.

The broken lines illustrate portions of the razor handle and form no part of the claimed design. The fine lines in the drawings are shadings which illustrate both curved and flat surfaces.
